UNITED STATES PATENT OFFICE.

CHARLES ALGERNON PARSONS, ALFRED QUINTIN CARNEGIE, AND GEOFFRY LAWRENCE PARSONS, OF NEWCASTLE-UPON-TYNE, ENGLAND; SAID GEOFFRY LAWRENCE PARSONS AND ALFRED QUINTIN CARNEGIE ASSIGNEES TO SAID CHARLES ALGERNON PARSONS.

VALVE-CONTROLLING DEVICE.

1,141,824.

Specification of Letters Patent.

Patented June 1, 1915.

Application filed February 3, 1913. Serial No. 746,026.

To all whom it may concern:

Be it known that we, CHARLES ALGERNON PARSONS, K. C. B., ALFRED QUINTIN CARNEGIE, and GEOFFRY LAWRENCE PARSONS, all 5 subjects of the King of Great Britain and Ireland, and all residing at Heaton Works, Newcastle-upon-Tyne, in the county of Northumberland, England, have invented certain new and useful Improvements in and 10 Relating to Valve-Controlling Devices of Plants Using Elastic Working Fluid from a Plurality of Sources, of which the following is a specification.

This invention relates to improvements in 15 controlling devices for the valves of plants using elastic working fluids from a plurality of sources at the same or at different pressures, its object being to enable the change from one source of supply to another to be 20 effected without variation in the speed of the turbine.

The invention consists in valve controlling devices for such plant comprising in respect of each valve to permit the opening 25 and closing thereof, means acting responsive to the speed regulating gear of the plant, and additional means acting responsive to pressure variations on the supply side of one valve, said additional means being entirely separate from the speed responsive means.

The invention also consists in valve controlling devices as hereinafter described.

The accompanying drawings illustrate 35 suitable valve arrangements and controlling devices therefor for turbines supplied with steam from two sources at different pressures, viz., a high pressure supply and a low pressure supply from a receiver, accumulator or the like.

According to the invention, means are provided for controlling the opening and closing of the valve in the delivery of each source of supply inversely to one another, 45 and dependently upon the pressure on the supply side of the low pressure valve, viz., upon the pressure on the side toward the receiver, accumulator or the like.

Figure 1 is a sectional elevation of one 50 form of the invention. Fig. 2 is an elevation partly in section of a modification.

As illustrated in Fig. 1, separately operated controlling means of this nature are

provided upon each valve, while in Fig. 2 a single operating device is adapted to move 55 the controlling means on both valves. These controlling means are separate from the speed regulating gear of the plant, and control the opening and closing of the valves independently of such gear.

In the form of the invention shown in Fig. 1, the high and low pressure valves are of the type in which the opening and closing is regulated by means of slides, *a*, controlling the exhaust of pressure fluid from the 60 under side of pistons, *b*, attached to the valve stems, *c*, the admission of the pressure fluid to the under side of these pistons being regulated by a suitable controlling valve, *d*. The ordinary speed regulating 65 gear of the plant, such as the governor, *e*, is arranged to operate by means of a lever, *f*, directly upon the slide, *a*, controlling the low pressure valve, *g*, and at the same time through the intermediary of the coupling, *h*, 70 and lever, *i*, upon the slide, *a*, controlling the high pressure valve, *j*. This speed regulating gear is arranged so that the turbine can 75 be driven from either the high or low pressure supply without a change of speed.

Mounted on the casing of both the high and low pressure valves is a cylinder, *k*, in which moves a piston, *m*. The upper side of this piston is open to the air, while the under side is connected to the space on the 85 supply side of the low pressure valve. The movement of the piston, *m*, may be controlled by means of suitable springs so that its movement will be proportional to the pressure of the low pressure supply. In the 90 case of the piston mounted on the casing of the low pressure valve, communication is effected by means of a passage, *n*, formed in the valve casing itself, while in the case of the piston in the cylinder mounted on the 95 high pressure valve, communication is effected by means of the pipe, *o*. In this way the under side of each of the pistons, *m*, is subjected to the pressure on the supply side of the low pressure valve, that is, to the 100 pressure on the side toward the receiver, accumulator or the like. Attached to each of the pistons, *m*, is a slide, *p*, which is adapted to control in parallel with the slides, *a*, the exhaust of the pressure fluid from the under 105 side of the piston, *b*. The two pistons, *m*,

and the attached slides, p , are arranged so that when the one controlling the exhaust from the piston, b , on the valve stem, c , of the low pressure valve, g , is in the position to maintain this valve in the closed position, the slide controlling the exhaust from the under side of the piston, b , attached to the stem, c , of the high pressure valve, j , is in the position to maintain this valve open. Since the slides, a and p , attached to both the high pressure and the low pressure valves act in parallel to control the exhaust of the pressure fluid acting on the pistons of these valves then so long as either of the slides, p , is in the position to maintain its corresponding valve shut, this valve will be in no way affected by the movement of the slide, a , received from the speed regulating governor, e , while if the slide, p , is in the position to maintain its corresponding valve open, then this valve is subject to the movements of the slide, a , from the speed regulating governor.

Both the slides, a and p , control the exhaust of the pressure fluid from the under side of the pistons, b , by allowing this fluid to escape through the passage, g , into the chamber, r , which may be connected to the condenser or atmosphere, as may be convenient.

It will be seen that the slides, p , with the pistons, m , which form the additional controlling means to both valves, operate independently upon the same pressure and also act inversely. The operation of the plant is as follows:—Assuming that there is a sufficient supply of low pressure steam, the pressure of this steam in front of the low pressure valve, g , will move the piston, m , connected to the slide, p , controlling the low pressure valve, into the position at which the slide itself closes the exhaust for the low pressure fluid from the under side of the valve, b , on the stem, c , of this low pressure valve, g . Under these conditions the low pressure valve is then under the control only of the slide, a , moved by the speed regulating governor, e . At the same time, the pressure in front of the low pressure valve moves the piston, m , and the slide, p , controlling the high pressure valve into the position in which the exhaust from the under side of the piston, b , attached to the stem, c , and the high pressure valve, j , is maintained open. In this way the high pressure valve remains closed. Should the supply of low pressure steam become insufficient so that the pressure in front of the low pressure valve falls, then the piston, m , and slide, p , attached to each valve, move so that the low pressure valve, g , begins to close while the high pressure valve is put under the control of the speed regulating gear of the plant and begins to open. Should the supply of low pressure steam cease alto-

gether the piston, m and slide, p , attached to each valve, move so that the low pressure valve, g , is maintained in its closed position while the high pressure valve is opened and under the control of the speed regulating gear of the plant.

It will be seen that any changes will be effected either gradually or instantaneously, the speed of changing over depending upon the character of the low pressure steam supply. The admission of high or low pressure steam is always under the control of the speed regulating gear of the plant, thus enabling the change from one source of supply to another to be effected without any variation in the speed of the turbine. The additional controlling means, viz., the pistons, m , and slides, p , determine when the high pressure and low pressure valves shall open or close, or how much of each valve shall be open simultaneously. These additional controlling means are also entirely separate from the speed regulating governor, e , and control only a complete or partial change over from one source of supply to the other.

In the form of the invention shown in Fig. 2, the high and low pressure valves are each provided with a slide, a , as in Fig. 1, which are operated in a similar manner by the speed regulating governor e . Both valves are also provided with additional slides, p . The slide, p , attached to the high pressure valve, however, is connected by means of a coupling, s , to a lever, t , attached to the slide, p , for the low pressure valve. On the low pressure valve in a similar manner as shown in Fig. 1, is mounted a cylinder, k , containing a piston, m , to which is attached the slide, p , of the low pressure valve. The operation of this arrangement is exactly similar to that as described in connection with the arrangement shown in Fig. 1, but it will be seen that the additional controlling means for the high and low pressure valves have been combined and arranged to be operated by a single piston, m . The movement of the slide, p , attached to the low pressure valve acts to control this valve inversely to the control of the high pressure valve effected by the slide, p , corresponding therewith.

It will be seen that according to this invention each valve is provided to permit the opening and closing thereof, with two sets of means, one set acting responsively to the speed regulating gear of the plant, and the other set acting responsively to pressure variations on the supply side of one valve, this latter means being entirely separate from that responsive to the speed regulating gear.

This invention may be applied generally to plant using elastic working fluid from a plurality of sources at the same or at differ-

ent pressures, and also that many modifications can be made in the mechanical arrangements for carrying it into effect without in any way departing from the spirit of 5 the same.

Having now described our invention what we claim as new and desire to secure by Letters Patent is:—

1. The combination with a mixed pressure turbine having low and high pressure supply conduits and valves controlling the same of independent motors for actuating each of said valves and separate pairs of controlling means for each of said motors 10 each of said pairs comprising a speed responsive device and a pressure responsive device said devices operating in series.
2. The combination with a mixed pressure turbine having low pressure and high pressure supply conduits and valves controlling the same of independent motors for actuating each of said valves separate independent speed responsive means in conjunction with each of said motors said means 15 acting simultaneously and in the same sense separate independent pressure responsive means in conjunction with said motors said pressure responsive means acting simultaneously and inversely.
3. The combination with a mixed pressure turbine having a low pressure and high pressure supply conduits and valves con- 20

trolling the same of independent motors for actuating each of said valves a relay slide valve for each of said motors a speed responsive device controlling said relay valves secondary slide valves beyond said relay valves and means responsive to the pressure in the low pressure supply conduit controlling said secondary valves and said motors 35 independently of the speed responsive device.

4. The combination with a mixed pressure turbine having low pressure and high pressure supply conduits and valves controlling the same of independent motors for actuating each of said valves a relay slide valve for each of said motors a speed responsive device controlling said relay valves simultaneously to open or close the same 40 secondary slide valves beyond said relay valves and means responsive to the pressure in the low pressure supply conduit controlling said secondary valves and said motors simultaneously and inversely independently 45 of the speed responsive device.

In testimony whereof, we affix our signatures in presence of two witnesses.
